ATION OF PENNSYLVANIA.

PRINTING DIE.

Application filed February 15, 1927. Serial No. 168,316.

Our invention relates to improvements in printing dies and particularly in dies of rubber, adapted to be applied to and removed from a carrier. The objects of the 5 invention are ease of handling, serviceability, and durability.

Our invention is illustrated in the accompanying drawings, in which Fig. I is a view in perspective of a die of our invention. 10 Fig. II is a view in perspective and to smaller scale of a carrier for dies, in this case a rocker, and showing a die of our invention in place upon it. Figs. III and IV are views to larger scale, illustrating 15 alternative forms which the metallic inlay, a feature of the die of our invention, may take.

The die 1, formed essentially of rubber will ordinarily be of rectangular shape and 20 of substantial thickness. The dimensions of the body part of a particular die (exclusive of the character raised upon its face and exclusive of the end flanges) are $\frac{3}{4}$ " x $1\frac{3}{16}$ " x $1\frac{3}{16}$ ". These dimensions are given by 25 way of example, not by way of limitation. Upon the face of the die the character 2 to be imprinted is raised,—in this instance it stands $\frac{1}{8}$ " high.

The body of the die is formed at its opposite ends with basal flanges 3. These flanges in the die whose dimensions are being given, extend $\frac{3}{2}$ " from the body part 30 and are $\frac{1}{16}$ " thick.

Molded within the rubber body and in 35 its basal part is an inlay 4 of metal. This inlay may, as is more particularly shown in Fig. III be of woven wire, or, as shown in Fig. IV it may be of perforate sheet metal. These two forms are given as illustrative, but not as an exhaustive presentation 40 of alternative forms. The inlay manifestly might consist of a succession of unconnected lengths of wire, extending from end to end of the die. It is essential only 45 that this inlay of metal be attenuated, and be capable of being united with the rubber into an integral whole. The inlay, as appears in Fig. I, extends into the basal flanges 3. Its opposite margins are folded 50 over, and these folded-over margins lie within the flanges 3.

The folding over of the margins of the inlay has these advantages: it greatly increases the rigidity and holding power of

the flanges; the edges of the inlay are 55 rounded, there are no projecting sharp points; the die as a whole is left sufficiently flexible in the middle for bending transversely, as may be required in application and removal, but elsewhere it is relatively 60 inflexible. The essential elasticity of the rubber remains, to render the die adequate in printing; the die is easy to make, inexpensive, and it is durable in high degree.

In Fig. II the method of use is illustrated. 65 A rocker 5 bears on its face pairs of opposite overhanging retaining strips 6, spaced apart at an interval corresponding to the length of the die body, exclusive of its base flanges; in this instance $\frac{3}{4}$ ", with suitable 70 allowance. The thickness of the strips is less than the height of the die from base flange to printing face, and the spaces beneath the strips are sufficient to receive the base flanges of the die. In making application, the die may be slid to position with its flanges 3 beneath strips 6, by being applied at the end of the rocker; or the die may be flexed medially until the distance between the edges of the flanges 3 is less than the distance between the opposite edges of strips 6. It may then be inserted between the strips and released; whereupon it will spring 75 to place. Removal may be effected in like manner. Manifestly the invention is not 80 limited to any particular dimensions; manifestly a single die member may carry a plurality of characters to be printed; manifestly if the die member be of great extent 85 in length and breadth relatively to thickness, its edges on every side or along as many sides as desired may be formed with reinforced basal flanges such as described 90 of the ends of the particular die shown in the drawings and described above.

We claim as our invention:

A printing die consisting of a block of rubber containing an inlay of metal, such block bearing on its face the character to be printed, and being formed at its ends 100 with opposite basal flanges, and said inlay being of attenuated form, with opposite folded-over margins, such folded-over margins extending within said basal flanges.

In testimony whereof we have hereunto 105 set our hands.

HAROLD R. WADE.
LEE M. HARLEY.
